UNITED STATES PATENT OFFICE.

PHINEAS B. MYERS, OF NEW YORK, N. Y.

DESIGN FOR A PAPER BOX.

SPECIFICATION forming part of Design No. 28,730, dated May 31, 1898.

Application filed April 27, 1898. Serial No. 679,044. Term of patent 3½ years.

to all whom it may concern.

Be it known that I, PHINEAS B. MYERS, a citizen of the United States, and a resident of New York, (Brooklyn,) county of Kings, and state of New York, have invented and produced a new and original Design for Paper boxes, of which the following is a specification, reference being had to the accompanying drawing, which represents a perspective view of my newly-designed paper box. The leading feature of my design consists in a paper box having sloping sides and being conventionalized representation of a fortress.

The letters *a* represent the sloping sides of box made in the form of a frustum. The

sides *a* are ornamented to represent brick-work *b*, with embrasures *c*, through which point cannons *d d'* beneath crossed American flags *e*, the whole being a conventionalized representation of a fortress.

The box is perforated within the muzzle of cannon *d'*, as illustrated by black shading in the drawing.

What I claim is—

The design for a paper box, substantially as herein shown and described.

PHINEAS B. MYERS.
